US00D962007S

(12) **United States Design Patent** (10) **Patent No.:** **US D962,007 S**
Madanat (45) **Date of Patent:** **** Aug. 30, 2022**

(54) **SYRUP DISPENSER**

(71) Applicant: **The International Company for Designs and Innovative Products, Amman (JO)**

(72) Inventor: **Sahar Anis Madanat, Amman (JO)**

(73) Assignee: **The International Company for Designs and Innovative Products, Amman (JO)**

(**) Term: **15 Years**

(21) Appl. No.: **29/731,072**

(22) Filed: **Apr. 10, 2020**

(51) LOC (13) Cl. **07-06**

(52) U.S. Cl.

USPC **D7/598; D9/764**

(58) **Field of Classification Search**

USPC D7/552.2, 596, 598, 602, 610, 612, D7/629-630, 701, 707; D9/424-425, D9/428-429, 519, 523-525, 529, D9/544-545, 549, 574, 764, 766, 905; D26/10; D11/184; D6/534, 677.1

CPC A47G 19/26; A47G 19/265; A47G 2400/061; A47G 2023/0691

(57) **CLAIM**

The ornamental design for a syrup dispenser, as shown and described.

DESCRIPTION

FIG. 1 is a top perspective view of a syrup dispenser of the claimed design;

FIG. 2 is a bottom perspective view of a syrup dispenser of the claimed design;

FIG. 3 is a front view of a syrup dispenser of the claimed design;

FIG. 4 is a rear view of a syrup dispenser of the claimed design;

FIG. 5 is a right-side view of a syrup dispenser of the claimed design;

FIG. 6 is a left-side view of a syrup dispenser of the claimed design;

FIG. 7 is a top view of a syrup dispenser of the claimed design; and,

FIG. 8 is a bottom view of a syrup dispenser of the claimed design.

The dashed lines shown in the drawings depict portions of the syrup dispenser that form no part of the claimed design.
